DESIGN FOR A COAT

Anthony Carnicelli, New York, N. Y.

Application June 22, 1938, Serial No. 77,982

Term of patent 3½ years

To all whom it may concern:

Be it known that I, Anthony Carnicelli, a citizen of the United States and residing in Manhattan, in the city, county, and State of New York, have invented a new, original, and ornamental Design for a Coat, of which the following is a specification, reference being had to the accompanying drawing, forming part thereof, wherein:

Fig. 1 is a front view of a coat showing my new design.

The characteristic features of my design reside in the specific matching fur collar, cuffs, buttons, and pockets in combination with the specific coat as shown.

I claim:

The ornamental design for a coat, substantially as shown and described.

ANTHONY CARNICELLI.
